EDWARD BOSTOCK, OF ALBANY, NEW YORK.

Letters Patent No. 67,487, dated August 6, 1867.

IMPROVEMENT IN ADJUSTABLE PARALLEL RULERS.

The Schedule referred to in these Letters Patent and making part of the same.

TO ALL WHOM IT MAY CONCERN:

Be it known that I, EDWARD BOSTOCK, of the city of Albany, county of Albany, and State of New York, have invented an Improved Adjustable Parallel Ruler; and I do hereby declare that the following, taken in connection with the drawings which accompany and form part of this specification, is a description of my invention sufficient to enable those skilled in the art to practise it.

This invention relates to an improvement in the construction of parallel rulers, and consists in securing to the ruler a rod or rods, upon which the gauge-bar or holder may slide, and in securing adjustably to the holder a sliding, graduated gauge, having thereon a straight-edge parallel with the ruler, and against which the ruler shall rest when moved back for ruling a line parallel to the one previously made. A parallel ruler embodying my invention is represented in the drawings, in which—

Figure 1 is a plan view of my ruler when closed.

Figure 2, the same when opened and its straight-edge adjusted for use; and

Figure 3, a cross-section taken in the line xx of fig. 2.

Like letters refer to like parts in the several figures.

A represents the ruler, having a bevelled edge, if preferred, on the side H against which the pencil or other marking instrument bears when in the act of ruling a line. This edge may preferably have a graduated scale thereon, as shown. B is the gauge-holder, through which the rods or bars C pass, so as to allow of adjustment for any required distance between the lines to be ruled. These rods are rigidly secured to the ruler A, or inserted therein in any proper manner, and project beyond it sufficiently to equal the breadth of bar B added to the longest distance that the bar may ever need to be moved back from the ruler. The outer ends of these rods have removable heads G', knobs, or their equivalents, thereon, to prevent bar B from sliding off, as well as to limit its range of motion and preserve its parallelism with the ruler when moved back to its extreme limit. As in the present instance I have represented the rods as passing through holes drilled or bored through the bar D, I have cut notches, as shown at G, in the outer edge, to receive these knobs. D is an adjustable slide, with a graduated scale marked thereon, having as part of the same, or rigidly secured thereto at right angles to its inner end, a long straight-edge, the object of which is to afford a firm rest for the edge M of the ruler when in contact with it, as hereinafter mentioned. The scale on slide D affords a ready means for adjusting the edge of this slide at any desired distance from the edge M. K is a longitudinal slot, to admit of this adjustment, and E is a pin secured to B, and having a screw-thread thereon. L is a thumb-nut adapted for this pin, and which serves to secure the slide firmly in any position to which it may be desired to adjust it. This slide is tightly steadied between the ways or plates I I. Instead of two rods or bars, C, one only may be used, if desired. In such case, it is to be placed centrally of the length of the ruler, and so adapted as not to interfere with the free action of the slide and its straight supporting-edge. The slide is preferably made of metal, but I do not confine myself to any particular material or materials either for the ruler or the other parts. By unscrewing or otherwise removing the knobs G', the ruler A may be withdrawn from B, and reversed, and the knobs replaced, so as to bring the bevelled edge H uppermost. It is then adapted for pencil ruling by draughtsmen and architects, and for other purposes where it is desirable to have a flat edge to rest on the material to be ruled, but when the bevelled edge is beneath, as shown in fig. 3, the ruler is adapted for ruling with ink, or for ordinary purposes. For the purpose of its more convenient use when so reversed, I mark a graduated scale on both sides of the ruler.

The operation of my device when in use is as follows: Suppose the rule is to be set for ruling parallel lines one-fourth of an inch apart, (as shown in fig. 2.) This setting is effected by drawing lath B back on the rods as far as the knobs G' will permit; next, by adjusting the straight-edge of slide D to within one-fourth of an inch of edge M, and then securing it tightly by the nut L. I now press the fingers on the lath B, then draw A back so that its rear edge M shall set closely against the straight-edge or gauge of slide D. I now rule a line, and then press the fingers on the lath A, and draw B back as far as the knobs or detents G' G' will allow, then draw back A as before, and rule another line, and so on as far as desired.

The simplicity of this device is evident: it has no complex parts, nor is it liable to derangement, while any tendency of the ruler A to be deflected out of true parallelism with B, when the pressure of the fingers is upon B only, is met and corrected by the straight-edge of D.

I am aware that parallel rulers have been made in which the ruler was connected with a parallel bar or lath, and operated and steadied by a complex system of toggle-levers and tooth-racks. These I dispense with.

What I claim as my invention is—

1. The employment in parallel rulers of an adjustable slide, having a straight supporting-edge thereon, as and for the purpose described.
2. In combination with such adjustable straight supporting-edge, one or more guides or rods, as and for the purpose set forth.
3. In combination with such adjustable straight supporting-edge, one or more guides or rods, having knobs or heads thereon, as and for the purpose set forth.
4. I claim such adjustable straight supporting-edge, when provided with a graduated scale thereon, as and for the purpose set forth.
5. The combination of the laths A and B with the rods or bars C C, for the purpose set forth.
6. The combination of the laths A and B, rod or rods C, and the straight supporting-edge, as and for the purpose set forth.
7. Providing the guide-rods with removable heads, to admit of reversing the ruler, relatively to a bar, B, so as to place its bevelled edge against or away from the material to be ruled, for the purpose set forth.

EDWARD BOSTOCK.
